UNITED STATES PATENT OFFICE.

CHARLES W. STRAN, OF CLEVELAND, OHIO.

HOT-AIR FURNACE.

No. 807,050.

Specification of Letters Patent.

Patented Dec. 12, 1905.

Application filed March 26, 1904. Serial No. 200,102.

To all whom it may concern:

Be it known that I, CHARLES W. STRAN, a citizen of the United States of America, residing at Cleveland, in the county of Cuyahoga and State of Ohio, have invented certain new and useful Improvements in Hot-Air Furnaces; and I hereby declare the following to be a full, clear, and exact description of the invention, such as will enable others skilled in the art to which it pertains to make and use the same.

This invention relates to improvements in hot-air furnaces, and pertains more especially to a hot-air furnace in which either solid fuel—such, for instance, as coal—or fluid fuel—such, for instance, as inflammable gas or vapor—can be burned.

One object of this invention is to provide the fire-pot of the furnace at its upper end and exteriorly with an annular interiorly-chambered enlargement, with the interior chamber of the said enlargement of the fire-pot in communication with a gas-supply pipe, with the inner side wall of the said chamber provided with downwardly and inwardly discharging orifices connecting the said chamber with the interior chamber of the fire-pot, and with inwardly and downwardly projecting deflectors integral with the fire-pot at the top of the discharging ends of the said orifices and instrumental in spreading the flame issuing from the said orifices during the operation of the furnace.

Another object is not only to effect the passage of air to be heated to and around the fire-pot and thence upwardly and over a dome-shaped casting or section mounted upon the upper end of the fire-pot, but also through upwardly and inwardly extending ducts with which the said dome-shaped section is provided and which overhang the interior chamber of the fire-pot and communicate, in common with an air-receiving chamber formed in and centrally of the top of the said dome-shaped section, over and centrally of the fire-pot chamber, with the said air-receiving chamber, placed in communication with the hot-air chamber above at different points.

Another object is to arrange a plurality of heating drums or radiators at different elevations above the outlet of the aforesaid dome-shaped section for the products of combustion ascending from the fire-pot chamber during the operation of the furnace and to conduct the said products of combustion successively through the different heating drums or

radiators in the passage of the said products of combustion to the smoke-flue of the furnace.

Another object is to conduct the air to be heated upwardly to and around, in, under, and over the different heating drums or radiators, respectively, during the passage of the said air upwardly through the hot-air chamber of the furnace.

The primary object of this invention is to utilize the products of combustion advantageously, so as to effect great economy in the consumption of fuel.

With these objects in view and to the end of realizing other advantages hereinafter appearing this invention consists in certain features of construction and combinations and arrangement of parts hereinafter described, and pointed out in the claims.

In the accompanying drawings, Figure 1 is a side elevation, in central vertical section, of a hot-air furnace embodying my invention. Fig. 2 is a top plan, in horizontal section, on line 2 2, Fig. 1. Fig. 3 is a side elevation in section on line 3 3, Fig. 1, looking in the direction indicated by the arrow. Figs. 4 and 5 are top plans, in horizontal section, on lines 4 4 and 5 5, respectively, Fig. 1.

Portions are broken away in Figs. 2 and 3 to more clearly show the construction.

Referring to the drawings, A (see Fig. 1) designates the ash-pit of the furnace, which ash-pit is formed by a suitably-shaped receptacle *a*, arranged at the bottom and centrally of the furnace, and B designates a doorway communicating with the ash-pit and closed at its outer end by a suitably-applied door *b*. A grate *C* is supported from the receptacle *a* and extends over the ash-pit. A fire-pot *D* is mounted upon the upper end of the receptacle *a*. The fire-pot *D* flares upwardly somewhat and is provided at its upper end and exteriorly with an interiorly-chambered annular enlargement *d*, which extends circumferentially of the fire-pot. The interior chamber 10 of the enlargement *d* of the fire-pot *D* is annular, extending circumferentially of the fire-pot and communicating at one side of the fire-pot with the gas-supply pipe *f*. The chamber 10 is provided in its inner side wall with orifices 12, which are arranged at short intervals circumferentially of the fire-pot and communicate with the said chamber at the top of the chamber. The orifices 12 extend downwardly and inwardly from the chamber 10 and communicate at their lower ends with the interior chamber 13 of the fire-pot *D*. The

fire-pot D is provided at the top of the lower and discharging end of each orifice 12 with a downwardly and inwardly projecting flame-deflector and flame-distributer, by which any 5 flame issuing from the said orifice during the operation of the furnace is deflected downwardly and toward the center of the fire-pot D and distributed circumferentially of the fire-pot. The flame-deflectors and flame-spreaders 10 14 are integral with the surrounding wall of the combustion-chamber 13 next above the discharging ends of the different orifices 12, respectively. Obviously, therefore, any flames issuing from the orifices 12 are advantageously 15 spread or distributed in heating the fire-pot D.

A dome-shaped section E is mounted upon the upper end of the fire-pot D and consists, preferably, of an iron casting. The upper portion of the dome-shaped section D is conical or gradually reduced transversely toward its upper end, as at 15. The outlet 16 in the dome E for the products of combustion arising within the fire-pot from the fuel burned within the said pot during the operation of 20 25 the furnace is formed at the upper end and centrally of the upper conical portion 15 of the dome E and is flanged upwardly and annularly, as at 17. The dome E is provided at one side with a doorway G, which is closed at 30 its outer end by a suitably-applied door g. The section E is provided at the top and centrally of its outlet 16 with an air-receiving pocket or chamber 18, which is arranged at an elevation above the doorway G and centrally 35 relative to the fire-pot. The chamber 18 is in communication with the upper ends of three ducts 20, which are also formed in the section E and extend upwardly and inwardly from the exterior and lower end of the 40 45 said section to the upper end and centrally of the said section. The ducts 20 are arranged at suitable intervals circumferentially of the fire-pot D and communicate at their lower ends with the cold-air-receiving chamber H, which extends around the ash-pit-forming receptacle a and upwardly around the fire-pot D. The chamber H is provided at its lower 50 55 end with air-inlets h, which communicate with the atmosphere exteriorly of the furnace. The air-chamber H is formed between the furnace-casing J and the ash-pit-forming receptacle a and the fire-pot D, the said casing being enough larger diametrically than the fire-pot to form the said chamber.

I would here remark that the chamber 18, as shown very clearly in Figs. 1, 2, and 3, is deepest where the ducts 20 connect therewith and is shallowest centrally and directly opposite the doorway G, so as to interfere as little 60 as possible with the shoveling of solid fuel through the said doorway and into the fire-pot.

The provision of a single casting to form the dome E, the chamber 18, and the ducts 20 65 constitutes a feature of no inconsiderable im-

portance. By this construction the fire-pot D and the dome or feed-section E are as readily assembled as would be the case if the chamber 18 and the ducts 20 were not provided. The ducts 20 are arranged wholly above the 70 fire-pot. The air passing through the said ducts and the chamber 18 prevents overheating of the dome E, and joints to be rendered and kept fluid-tight at the ends of the said ducts are avoided.

The casing J extends upwardly a suitable distance above the dome E and above the said dome forms the hot-air chamber I of the furnace. The casing J is provided at the top of the furnace with apertures i, which form the 80 air-outlets of the hot-air chamber and through which the hot-air is conducted to the place or places desired.

Three radiator-forming heating-drums L, P, and R are arranged within and centrally of 85 the hot-air chamber I above the dome E, which drums are arranged at different elevations, respectively. The lowermost drum L is annular and rests upon the upper conical portion 15 of the dome E and has its interior 90 chamber l communicating at the bottom and centrally with the outlet 16 of the interior chamber of the said dome. Preferably the interior chamber of the drum L is provided at the bottom and centrally with a downwardly 95 and annularly flanged inlet 23. The flange 24, which extends around the inlet 23, rests upon the conical portion 15 of the dome E.

The drum L extends over and is arranged 100 a short distance above an annular conical deflector m, which is supported from the furnace-casing J in any approved manner and overhangs the conical upper portion 15 of the dome E, which deflector is enough larger diametrically than the said dome to form an annular space 25 between the said dome and the 105 said deflector, which space communicates at the upper end of the deflector with the hot-air chamber I above and is in communication at the lower end of the deflector with the cold-air chamber H below. The deflector m not only causes the air ascending through the cold-air chamber H to pass over the dome E, but prevents a straight upward passage of air, and being arranged above the air-receiving 110 115 ends of the ducts 20 insures an adequate supply of air to the said ducts.

The interior chamber l of the drum L is provided, in the top wall thereof, with two upwardly and annularly flanged outlets 26, arranged, preferably, at opposite sides, respectively, of a vertically-arranged air-flue 27, with which the central or intermediate drum P is centrally provided. The flue 27 depends into the opening 28 centrally of the annular 120 125 drum L. The opening 28 communicates at its lower end with the air-chamber 18 and is in communication at its upper end with the hot-air chamber I. The flue 27 communicates at its lower end with the opening 28, and con- 130

sequently with the air-chamber 18, and is in communication at its upper end with the hot-air chamber I.

The intermediate drum P is provided with two interior chambers 30, arranged at opposite sides, respectively, of the air-flue 27, as shown in Figs. 1 and 4. Each chamber 30 is provided at the bottom with a downwardly and annularly flanged inlet 32. The inlets 32 of the chambers 30 register with the different outlets 26, respectively, of the chamber l of the drum L. The flanges 33, which are formed upon the drum P and extend around the inlets 32, are shown snugly embraced by the flanges 29, which are formed upon the drum L and extend around the outlets 26. The drum P is provided also with two interior passage-ways 34, which extend, as shown in Fig. 4, along the outer side of the different chambers 30, respectively. The passage-ways 34 communicate at one end with the different chambers 30, respectively, and are in communication at their other end with the inlet 32 of the different chambers 30, respectively.

The uppermost drum R is arranged a short distance above the intermediate drum P and extends over the upper end of the air-flue 27. The bottom of the drum R is provided with two downwardly and annularly flanged apertures 35, with the flanges 36, which extend around the said apertures, snugly fitting, as shown in Figs. 4 and 5, interiorly of the annular flanges 37, which are formed upon the drum P and extend around the aperture 38, formed in the top of the drum P. The apertures 35 and 38 establish communication between the chambers 30 of the drum P and two passage-ways 40, with which the drum R is interiorly provided. The passage-ways 40 are arranged at opposite sides, respectively, of the drum R. The said passage-ways 40 therefore communicate at one end with the apertures 35 and are in communication at their other end with the smoke-flue K. The uppermost drum R is contained within and arranged centrally of an air-chamber 42, which is formed within the hot-air chamber I above the intermediate drum P and is provided at the top and centrally with an air-outlet 43, communicating with the said hot-air chamber.

By the construction hereinbefore described it will be observed that the lowermost drum L is supported at its depending annular flange 24 from the upper conical portion 15 of the dome E; that the intermediate drum P is mounted upon the flanges 29, formed upon the lowermost drum L around the outlets 26 of the interior chamber of the last-mentioned drum; that the uppermost drum R is mounted upon the flanges 37, formed upon the intermediate drum P around the outlets 38 of the interior chambers of the said intermediate drum; that the products of combustion arising from the interior chamber of the fire-pot dur-

ing the operation of the furnace pass through 65 the outlet 16 of the dome E into the interior chamber l of the lowermost drum L and from within the said chamber at the outlets 26 of the said chamber into the interior chambers 30 of the intermediate drum P and from the last- 70 mentioned chambers at their outlets 38 into the passage-ways 40 of the uppermost drum R and thence to the smoke-flue; that the cold air passing upwardly into the chamber H around the ash-pit-forming receptacle a and upwardly around the fire-pot D passes partially through the ducts 20 of the dome E and through the chamber 18 and connected opening 28 into the hot-air chamber I; that the intermediate drum P spreads the air passing in under 80 the said drum from the opening 28 over the lowermost drum L; that air passes not only through the opening 28 around the air-flue 27, but also through the said flue into the chamber 42, which contains the uppermost 85 drum R; that the air thus passing into the said chamber 42 is spread or distributed by the said drum R over the intermediate drum P and passes around and over the uppermost drum R through the outlet 43 of the chamber 90 42 into the hot-air chamber I, and that air passing from the exterior of the fire-pot and passing above the lower and air-receiving ends of the ducts 20 to and in under the deflector m is deflected inwardly by the said 95 deflector over the conical portion 15 of the dome E and thence passes upwardly to and against the exterior of the bottom of the lowermost drum L and thence through the hot-air chamber I. It will be observed, therefore, that by the construction hereinbefore described the products of combustion arising from fuel consumed within the combustion-chamber 13 are utilized economically and that the air to be heated is so distributed during 100 its upward passage relative to the heat-radiating surfaces that the consumption of fuel required to adequately heat the air is reduced to a minimum.

What I claim is—

1. A hot-air furnace comprising a fire-pot; the hot-air chamber above; a dome mounted upon the fire-pot and provided at the top and centrally with an outlet; means for conducting products of combustion from the said outlet; the cold-air chamber arranged exteriorly of the fire-pot and extending upwardly next exteriorly of the dome and in communication with the atmosphere exteriorly of the furnace; a plurality of ducts extending upwardly 115 and inwardly from the exterior and lower end of the dome, which ducts communicate at their lower ends with the aforesaid cold-air chamber, and an air-chamber formed in and centrally of the top of the dome and open at the top, and the last-mentioned air-chamber being in communication with the aforesaid ducts and with the aforesaid hot-air chamber and

arranged centrally of the aforesaid outlet so as to be exposed exteriorly to products of combustion ascending from the fire-pot.

2. A hot-air furnace comprising a fire-pot; 5 the hot-air chamber above; a dome mounted upon the fire-pot and consisting of a single casting provided at the top and centrally with an outlet for products of combustion arising from within the fire-pot; means for conducting products of combustion from the said outlet; the cold-air chamber arranged exteriorly of the fire-pot and extending upwardly next exteriorly of the dome and in communication with the atmosphere exteriorly of the furnace; 10 a plurality of ducts formed in the aforesaid casting and extending upwardly and inwardly from the exterior and lower end of the dome, which ducts are arranged wholly above the fire-pot and communicate at their lower ends 15 with the aforesaid cold-air chamber, and an air-chamber formed in and centrally of the upper portion of the aforesaid casting and open at the top, and the last-mentioned air-chamber being in communication with the 20 aforesaid ducts and with the aforesaid hot-air chamber and arranged centrally of the aforesaid outlet so as to be surrounded by products of combustion ascending from the fire-pot.

3. A hot-air furnace comprising a fire-pot; 30 a dome mounted upon the fire-pot and provided; at the top, with an outlet for the products of combustion arising from within the fire-pot; a cold-air chamber arranged exteriorly of the fire-pot and dome and in communication with the atmosphere exteriorly of the furnace; a hot-air chamber above the dome and provided with air-outlets; a radiator-forming interiorly-chambered heating-drum arranged above the dome and annular to form 35 an opening arranged centrally of the drum, which opening is in communication, at its upper end, with the hot-air chamber, and with the interior chamber of the drum provided, at the bottom and centrally, with an inlet communicating with the outlet of the dome; a plurality of ducts extending upwardly and inwardly from the exterior and lower end of the dome, which ducts communicate, at their upper ends, with the aforesaid opening and are 40 in communication, at their lower ends, with the cold-air chamber, and means for conducting products of combustion from the interior chamber of the drum.

4. A hot-air furnace comprising a fire-pot; 55 a dome mounted upon the fire-pot and provided, at the top, with an outlet for the products of combustion arising from within the fire-pot, which dome has its upper portion conical; a cold-air chamber arranged exteriorly 60 of the fire-pot and dome and in communication with the atmosphere exteriorly of the furnace; a hot-air chamber above the dome and provided with air-outlets; a radiator-forming interiorly-chambered heating-drum 65 arranged above the dome and annular to form

an opening arranged centrally of the drum, which opening is in communication, at its upper end, with the hot-air chamber, and with the interior chamber of the drum provided, at the bottom and centrally, with an annularly 70 and downwardly flanged inlet communicating with the outlet of the dome, with the flange, which extends around the said inlet, resting upon the aforesaid conical portion of the dome; a plurality of ducts extending upwardly and 75 inwardly from the exterior and lower end of the dome, which ducts communicate, at their upper ends, with the aforesaid opening and are in communication, at their lower ends, with the cold-air chamber, and means for conducting products of combustion from the interior chamber of the drum.

5. A hot-air furnace comprising a fire-pot; a dome mounted upon the fire-pot and provided, at the top, with an outlet for the products of combustion arising from within the fire-pot, which dome has its upper portion conical; a cold-air chamber arranged exteriorly of the fire-pot and dome and in communication with the atmosphere exteriorly of the furnace; the hot-air chamber above; an annular conical deflector overhanging the aforesaid conical portion of the dome, which deflector is large enough diametrically to form an annular space between it and the dome, which 80 space communicates, at the upper end of the deflector, with the hot-air chamber above and is in communication, at its lower end, with the cold-air chamber below; a radiator-forming interiorly-chambered heating-drum arranged a suitable distance above and extending over the deflector, which drum is annular to form an opening arranged centrally of the said drum, which opening is in communication, at its upper end, with the hot-air chamber, 85 and with the interior chamber of the drum provided, at the bottom and centrally, with an inlet communicating with the outlet of the dome; means for conducting air from the cold-air chamber upwardly and inwardly to the aforesaid opening, and means for conducting 90 products of combustion from the interior chamber of the drum.

6. A hot-air furnace comprising a fire-pot; a dome mounted upon the fire-pot and provided, at the top, with an outlet for the products of combustion arising from within the fire-pot; the furnace-casing extending around the fire-pot and dome and large enough in dimensions to form the hot-air chamber 115 above and the cold-air chamber below, with the latter arranged exteriorly of the fire-pot and dome and in communication with the atmosphere exteriorly of the furnace; an annular conical deflector supported from the furnace-casing and overhanging the upper portion of the dome, which deflector is large enough diametrically to form an annular space between it and the dome, which space 120 communicates, at the upper end of the deflector, with the hot-air chamber above and the cold-air chamber below; a radiator-forming interiorly-chambered heating-drum arranged above the dome and annular to form 125 an opening arranged centrally of the drum, which opening is in communication, at its upper end, with the hot-air chamber above and with the interior chamber of the drum provided, at the bottom and centrally, with an inlet communicating with the outlet of the dome; means for conducting air from the cold-air chamber upwardly and inwardly to the aforesaid opening, and means for conducting 130 products of combustion from the interior chamber of the drum.

5 reflector, with the hot-air chamber above and is in communication, at its lower end, with the cold-air chamber below; a radiator-forming interiorly-chambered heating-drum arranged a suitable distance above and extending over the deflector, which drum is annular to form an opening arranged centrally of the drum, which opening is in communication, at its upper end, with the hot-air chamber and 10 with the interior chamber of the drum provided, at the bottom and centrally, with an inlet communicating with the outlet of the dome; several upwardly and inwardly extending ducts arranged at suitable intervals around 15 the dome and communicating, at their upper ends, with the aforesaid opening, which ducts are in communication, at their lower ends and below the aforesaid deflector, with the cold-air chamber, and means for conducting products of combustion from the interior chamber of the drum.

7. A hot-air furnace comprising a fire-pot; the cold-air chamber arranged exteriorly of the fire-pot and in communication with the 20 atmosphere exteriorly of the furnace; the hot-air chamber above; a radiator-forming interiorly-chambered heating-drum provided, at the bottom, with an inlet communicating with the interior chamber of the fire-pot; a smoke-25 flue in communication with the interior chamber of the drum; several ducts extending upwardly and inwardly over the fire-pot and in communication, at their upper ends, with the hot-air chamber and communicating, at their 30 lower ends, with the aforesaid cold-air chamber, and means for guiding air ascending next exteriorly of the fire-pot into the said ducts.

8. A hot-air furnace comprising a fire-pot; a cold-air chamber arranged exteriorly of the 35 fire-pot and in communication with the atmosphere exteriorly of the furnace; the hot-air chamber above; a radiator-forming interiorly-chambered heating-drum arranged a suitable distance above the fire-pot, and annular to form an opening arranged centrally of the drum, which opening is in communication, at its upper end, with the hot-air chamber, and with the interior chamber of the drum provided, at the bottom and centrally, 40 with an inlet in communication with the interior chamber of the fire-pot; a plurality of upwardly and inwardly extending ducts communicating, at their upper ends, with the aforesaid opening and in communication, at 45 their lower ends, with the cold-air chamber, and means for conducting products of combustion from the interior chamber of the drum.

9. A hot-air furnace comprising a fire-pot; a cold-air chamber arranged exteriorly of the fire-pot and in communication with the atmosphere exteriorly of the furnace; the hot-air chamber above; a radiator-forming interiorly-chambered heating-drum arranged a 55 suitable distance above the fire-pot and an-

nular to form an opening arranged centrally of the drum, which opening is in communication, at its upper end, with the hot-air chamber, and with the interior chamber of the drum provided, at the bottom and centrally, 70 with an inlet which is in communication with the interior chamber of the fire-pot; a plurality of upwardly and inwardly extending ducts communicating, at their upper ends, with the aforesaid opening and in communication, at 75 their lower ends, with the cold-air chamber; another radiator-forming interiorly-chambered heating-drum arranged a suitable distance above the aforesaid annular drum and provided centrally with an upright air-flue 80 and having its interior in communication with the interior chamber of the aforesaid annular drum, said air-flue being in communication, at its upper end, with the hot-air chamber and communicating, at its lower end, with 85 the aforesaid ducts, and means for conducting products of combustion from the interior chamber of the upper drum.

10. A hot-air furnace comprising a fire-pot; a dome mounted upon the fire-pot and provided with an outlet for the products of combustion arising from within the fire-pot; the furnace-casing extending around the fire-pot and dome and large enough in dimensions to form the hot-air chamber above and the cold-air 90 chamber below, with the latter arranged exteriorly of the fire-pot and dome and in communication with the atmosphere exteriorly of the furnace; a suitably-supported deflector overhanging the upper portion of the dome, 95 which deflector is arranged to form a space between it and the dome, which space communicates with the hot-air chamber and with the cold-air chamber; a radiator-forming interiorly-chambered heating-drum arranged a 100 suitable distance above and extending over the deflector and having an interior chamber communicating with the outlet of the dome, which drum is shaped to form an opening 105 which is arranged centrally of the drum and communicates with the hot-air chamber; several upwardly and inwardly extending ducts arranged at suitable intervals around the dome and communicating at their upper ends with the aforesaid opening, which ducts are 110 in communication at their lower ends and in under the aforesaid deflector with the cold-air chamber, and means for conducting products of combustion from the interior chamber of the drum.

11. A hot-air furnace comprising a fire-pot; a dome mounted upon the fire-pot and provided with an outlet for the products of combustion arising from within the fire-pot; the furnace-casing extending around the fire-pot 115 and dome and large enough in dimensions to form the hot-air chamber above and the cold-air chamber below, with the latter arranged exteriorly of the fire-pot and dome and in communication with the atmosphere exte- 120 125 130

riorly of the furnace; a suitably-supported deflector overhanging the upper portion of the dome, which deflector is arranged to form a space between it and the dome, which space 5 communicates with the hot-air chamber and with the cold-air chamber; several upwardly and inwardly extending ducts arranged at suitable intervals around the dome and in communication at their upper ends with the 10 hot-air chamber, which ducts are in communication at their lower ends and in under the aforesaid deflector with the cold-air chamber, and means for conducting products of combustion from the outlet of the dome.

15 12. A hot-air furnace comprising a fire-pot; a dome mounted upon the fire-pot and provided with an outlet for the products of combustion arising from within the fire-pot; the furnace-casing extending around the fire-pot 20 and dome and large enough in dimensions to form the hot-air chamber above and the cold-air chamber below, with the latter arranged exteriorly of the fire-pot and dome and in communication with the atmosphere exteriorly of the furnace; a deflector supported from the furnace-casing and extending around and overhanging the upper portion of the dome, which deflector is arranged to form a space between it and the dome, which space 25 communicates with the hot-air chamber and with the cold-air chamber; a radiator-forming interiorly-chambered heating-drum arranged a suitable distance above and extending over the deflector, which drum is shaped 30 to form an opening centrally of the drum, with the said opening in communication with the hot-air chamber, and with the interior chamber of the drum in communication with the outlet of the dome; several upwardly and 35 inwardly extending ducts arranged at suitable intervals around the dome and communicating, at their upper ends, with the aforesaid opening, which ducts are in communication, at their lower ends and below the aforesaid deflector, with the cold-air chamber, and means 40 for conducting products of combustion from the interior chamber of the drum.

13. A hot-air furnace comprising a fire-pot; a dome mounted upon the fire-pot and having 45 an upper conical portion provided with an outlet for the products of combustion arising from within the fire-pot; means for conducting products of combustion from the said outlet; the furnace-casing extending around the 50 fire-pot and dome and large enough in dimensions to form the hot-air chamber above and the cold-air chamber below, with the latter arranged exteriorly of the fire-pot and dome and in communication with the atmosphere 55 exteriorly of the furnace; a deflector supported from the furnace-casing and extending around and overhanging the aforesaid conical portion of the dome, which deflector is 60 large enough diametrically and arranged to 65 form a space between it and the dome, which

space communicates with the hot-air chamber below, and several upwardly and inwardly extending ducts arranged at suitable intervals around the dome and in communication, at their upper ends, with the aforesaid hot-air 70 chamber, which ducts are in communication, at their lower ends and below the aforesaid deflector, with the cold-air chamber.

14. A hot-air furnace comprising a fire-pot; the hot-air chamber above; a dome mounted 75 upon the fire-pot and provided with an outlet for products of combustion arising within the fire-pot; means for conducting products of combustion from the said outlet; the cold-air chamber arranged exteriorly of the fire-pot and extending upwardly next exteriorly of the dome and in communication with the atmosphere exteriorly of the furnace; a plurality of ducts extending upwardly and inwardly from the exterior and lower end of 80 the dome, which ducts communicate, at their lower ends and above the fire-pot, with the aforesaid cold-air chamber; an air-chamber arranged centrally of and formed in the upper portion of the dome and in communication 85 with the said ducts and with the aforesaid hot-air chamber, and a deflector overhanging the dome and arranged to form a space between the deflector and the dome above the lower and air-receiving ends of the 90 aforesaid ducts.

15. A hot-air furnace comprising a fire-pot; the hot-air chamber above; a dome mounted upon the fire-pot and consisting of a single casting, which dome is provided with an outlet for products of combustion arising from within the fire-pot; means for conducting products of combustion from the said outlet; the cold-air chamber arranged exteriorly of the fire-pot and extending upwardly next exteriorly of the dome and in communication with the atmosphere exteriorly of the furnace, and several ducts formed in the aforesaid casting and extending upwardly and inwardly from the exterior and lower end of the dome, 100 which ducts communicate, at their lower ends, with the aforesaid cold-air chamber, and are in communication, at their upper ends, with the aforesaid hot-air chamber; a deflector overhanging and extending around the aforesaid 105 casting and arranged to form a space between the deflector and the casting above the lower and air-receiving ends of the aforesaid ducts.

16. A hot-air furnace comprising a fire-pot; the hot-air chamber above; a dome mounted 110 upon the fire-pot and comprising a casting provided at the top of the dome with an outlet for products of combustion arising from within the fire-pot, which dome is provided at the front of the furnace with an inlet; 115 means for conducting products of combustion from the aforesaid outlet; the cold-air chamber arranged exteriorly of the fire-pot and extending upwardly next exteriorly of the dome and in communication with the atmosphere 120

- exteriorly of the furnace; a plurality of ducts formed in the aforesaid casting at suitable intervals round the dome rearward of the aforesaid inlet and extending upwardly and inwardly from the exterior and lower end of the dome, which ducts communicate, at their lower ends, with the aforesaid cold-air chamber, and an air-chamber formed in and centrally of the upper portion of the aforesaid casting and open at the top, and the last-mentioned air-chamber being in communication with the aforesaid ducts and with the aforesaid hot-air chamber and decreasing in depth in the direction of the aforesaid inlet.
- 15 17. A hot-air furnace comprising a fire-pot; a dome mounted upon the fire-pot and provided at the top with an outlet for the products of combustion arising from within the fire-pot, which dome has its upper portion conical; a cold-air chamber arranged exteriorly of the fire-pot and dome and in communication with the atmosphere exteriorly of the furnace; a hot-air chamber above the dome;
- a radiator-forming interiorly-chambered heating-drum arranged above the dome, with the 25 interior chamber of the drum in communication with the outlet of the dome; an air-chamber formed at and centrally of the aforesaid conical portion of the dome and below the aforesaid drum; a plurality of ducts extending upwardly and inwardly from the exterior and lower end of the dome, which ducts communicate, at their upper ends, with the last-mentioned chamber and are in communication, at their lower ends, with the aforesaid cold-air chamber, and means for conducting products of combustion from the interior chamber of the drum.
- 20 In testimony whereof I sign the foregoing specification, in the presence of two witnesses, 40 this 23d day of March, 1904, at Cleveland, Ohio.

CHARLES W. STRAN.
